ROPE LOCK

Charles A. Boyer, Winona Lake, Ind.

Application November 2, 1948, Serial No. 57,851

1 Claim. (Cl. 24—133)

1

This invention relates to a rope lock of a type which may advantageously be used when weights, anchors, mechanical devices, scaffolds, awnings, etc. are to be suspended at varying heights.

Most rope locking devices in general use are defective in that they tend to pinch, chafe and cause abrupt bends in the rope, resulting in rope weakening and breakage of fibers at the point of locking contact.

My invention which provides for positive friction locking eliminates undue rope wear at the point of locking contact by providing a flat jaw having a relatively large friction contact area, and by eliminating pinching and pressure at places where the rope bends and turns.

The objects of my invention are:

(1) To provide a rope locking device which will minimize the wear and tear on the rope at the locking point;

(2) To provide a rope locking device wherein the locking device can be controlled remotely by means of the rope itself; and

(3) To provide a rope locking device which is efficient, trouble free, and economical to manufacture.

With reference to the drawing which illustrates the rope lock of my invention in a preferred form:

Fig. 1 is a side elevational view;

Fig. 2 is a top plan view thereof;

Fig. 3 which is a vertical section, taken on line 3—3 of Fig. 2, shows the pendulum sustained upwardly by the rope while in a horizontal position and free to run in or out;

Fig. 4 is a vertical section, similar to Fig. 3, showing the free end of the rope lowered sufficiently to permit the pendulum to swing down to the point that its eyelet engages opposite sides of the rope for an enhanced frictional contact therewith; and

Fig. 5 is a vertical section, similar to Fig. 3, showing the rope locked as the result of full engagement therewith by the pendulum jaw on its top surface and by the coacting base on the under surface of the rope.

My improved rope locking device comprises an elongated frame having a base 10 from which rises two spaced guide walls 11 which extend to a forward point for interconnection and for support between them of a pin 12 whereon is rotatably mounted a sheave 13. The base is provided with one or more holes 14 each to receive a screw or bolt 15 for securing the frame to a supporting structure S, such as the bow deck of a small boat.

Between the guide walls 11 is pivotally suspended, as by a pin 29, a pendulum P which is mounted to swing lengthwise of the frame. This

2

pendulum comprises cheeks 21 which support between them an elongated relatively flat jaw 22 at a rearwardly disposed point, as shown. At its forward end the jaw connects with a tongue 23 whose spacing from the pendulum axis is somewhat less than is that of the jaw 22; because of this relationship, the tongue will remain spaced from the base 10 a further distance than the jaw when the latter is swung down into a position of substantial parallelism with the base.

A hole 30 is formed through the tongue and is desirably reenforced with an eyelet 31 which provides a smooth and round edge therefor. The internal diameter of the eyelet should be substantially greater than the diameter of the rope R which is passed therethrough. Preferably the clearance within the hole is ample to accommodate ropes varying somewhat in diameter. The axial position of the pendulum may also be adjusted, according to the size of the accommodated rope, as by seating the ends of the axial pin 20 in another pair of registering holes 32 located at a different distance from the base of the frame.

Although relatively flat in the direction of its length, the jaw 22 is desirably concave from side to side and provided thereacross with ribs a also concave from end to end. Such a contour adapts the jaw for better and more effective gripping with the top face of the rope R when brought into engagement therewith. Directly opposite the jaw, when the latter is in engagement with the rope, is a transversely concave area in the base 10 provided with concave ribs b extended thereacross. Such a surface is also adapted for better and more effective engagement with the rope when the latter is pressed down thereupon by the jaw 22 thereabove. These coacting engaging surfaces of the jaw and base are sufficiently elongated to afford an extended area of compressive contact with the rope upon opposite faces thereof.

When the base of the rope lock is horizontally disposed, as suggested in the drawing, the jaw 22 which is extended outwardly to one side of a vertical line passing through its axis will act as a weight tending to swing the pendulum downwardly to a point where engagement takes place between the jaw and the top of the rope over an elongated portion thereof. Desirably the pendulum is light in weight and to this end it may be stamped from aluminum or one of its alloys. But very little gravity force is needed to assure a swinging movement of the pendulum toward the base.

The rope end beyond the sheave 13 is normally attached to some supported object so that the rope is tensioned throughout its portion which passes between the guide walls 11 of the elongated frame.

gated frame. These walls serve to guide the rope so that its relative position through the frame remains substantially unchanged at all times. This is true even though the free end of the rope be held in a position of misalignment relative to the frame.

The locked position of the parts is indicated in Fig. 5. Here it will be noted the jaw 22 is swung down toward the base so that its cross ribs *a* are engaged with the top face of the rope whose under face is rested upon the base 10 within the concave area thereof where the cross ribs *b* are provided. The gripping area, both above and below, is elongated in the direction of the rope length, and also increased circumferentially thereof due to the transverse concave contours thereof, consequently the frictional contact therewith is effectively distributed. Forwardly of the jaw the rope rises from the base and in doing so passes obliquely upwardly through the hole 30 in the tongue 23 of the pendulum. From this point on the rope proceeds forwardly over the sheave 13 to connect with its supported object.

The pull of the rope is resisted by the jaw 22 which is positioned to the rear of a line passing vertically through the movement axis of the pendulum. Any further movement of the pendulum, i. e. in a clockwise direction as indicated in Fig. 5, would only apply to the rope an augmented compressive force tending to secure it more firmly. The hole 30 through the tongue, as shown in Fig. 5 lies forwardly of a line extending vertically through the movement axis of the pendulum; it also lies further removed from the base than does the jaw 22. There is consequently no compression of the rope either where it enters or leaves the opening except such as is occasioned by the tension in the rope at these points of bending.

In Fig. 5 I have diagrammed by the dot and dash lines *x*—*x* and *y*—*y* the endwise limits of the elongated jaw. Here it will be observed that the jaw lies in its entirety to one side of a vertical line passing through the movement axis of the pendulum, and furthermore that the outermost portion of the jaw lies more than 45° away from the vertical, thereby placing it in an octant that is immediately below the horizontal. As a result, the jaw movement is preponderantly downwardly when reaching the locking position of Fig. 5. From this it follows that the jaw ribs *a*, when in engaging with the rope, will move primarily downwardly so as to minimize objectionable chafing which would otherwise result.

To release the lock, the free end of the rope is lifted to disestablish all contact with the base 10. While this is being done, the rope will normally remain under tension so as to take up an initial position about as indicated in Fig. 4. If the rope be further lifted, the pendulum will be raised to the position of Fig. 3 where the rope engages with the hole eyelet 31 at only its topmost point.

Assuming that the lock is to be operated, the rope is payed out to the desired point while maintained in a position that is substantially horizontal or higher. During this movement the light weight pendulum is sustained in an upper position of minimum friction. When the releasing movement of the rope has approached the point where it is to be held, the free end of the rope need be lowered only slightly—to about the position of Fig. 4. Here the pendulum is shown as having swung downwardly to the point that the hole eyelet 31 is in engagement with

the rope on both its top and underfaces. As a result, the friction of the pendulum on the rope is increased by at least double, thereby greatly enhancing the down pull on the pendulum so as to accelerate and complete locking engagement of its jaw with the rope. The normal gravity action is, therefore, supplemented by the out-pull of the rope when this point is reached, thereby producing a rapid and sure completion of the pendulum movement to the locking position that is desired.

The term "pendulum" as used herein applies more particularly to the rope locking device when the base is horizontally disposed. It is obvious, of course, that the base may be inclined at various angles, or even be positioned vertically in which event the gravity action of the pendulum would be modified. It is contemplated in any such case that the pendulum may be weighted, if necessary, to assure that it will be gravity operated in the manner already described.

I claim:

A rope lock including a guide frame having a flat elongated base and provided with spaced guide walls, and a pendulum pivotally mounted between the guide walls to swing lengthwise of the frame and comprising spaced cheeks and a connecting bottom consisting of an elongated relatively flat jaw extending rearwardly along the base in parallelism therewith when the pendulum is in engaging position to produce a long straight clamping portion, a flat tongue constituting an intermediate portion of the bottom of the pendulum and inclined upwardly slightly, when the jaw is in parallelism with the base, to produce a slight change in the direction of the rope and a front section, the front of the bottom of the pendulum being disposed in substantially the plane of the tongue and provided with a rope receiving opening presenting rounded edges to the rope and producing abrupt bends in the rope remote from the straight clamping portion of the pendulum, the jaw being concave from side to side and provided with an extended area of concave transverse ribs and the base being provided with an extended area of transverse ribs.
